UNITED STATES PATENT OFFICE.

WILLIAM C. CARR, OF BUFFALO, NEW YORK, ASSIGNOR TO THE AUTOMATIC TRANSPORTATION COMPANY, OF BUFFALO, NEW YORK, A CORPORATION OF ARIZONA.

INDUSTRIAL TRUCK.

Application filed January 20, 1923. Serial No. 613,944.

To all whom it may concern:

Be it known that I, WILLIAM C. CARR, a citizen of the United States, residing at 2933 Main Street, Buffalo, in the county of Erie and State of New York, have invented a new and useful Improvement in Industrial Trucks, of which the following is a specification.

This invention relates to improvements in 10 electrically operated industrial trucks such as are provided with load supporting platforms and are used in manufacturing establishments for the quick and easy transport of objects or materials from one point to 15 another, the loads being placed on the platforms either directly or by means of loading skids.

The invention secures the advantages of 20 maximum flexibility in the regulation of the speed of operation, any desired operating speed being available, the use of slow and safe accelerating speed which is particularly desirable when fragile or breakable objects are being transported, certainty and maximum 25 facility of control, a substantially longer efficient life of the truck mechanism, the elimination of arcing between the relatively movable contacts of the switches, reduction of the cost of operation and maintenance, and the greatest degree of safety, 30 involving protection to the truck and its load, objects along the line of travel and the person of the operator.

The principal object of the invention is to 35 provide simple and effective mechanism responsive to a single controlling element of an industrial truck, preferably a foot pedal, whereby said element is effective to regulate the supply of current to the motor, to select 40 the speed at which the motor is driven, and preferably to control the action of the brake.

A further object is to provide mechanism, 45 which, having the characteristics stated, makes possible an exceedingly simple and compact switch organization, an advantage of value owing to the necessity for lightness and compactness in the organization of the mechanism of industrial trucks which must be capable of easy and certain handling in 50 small and congested areas where their use is frequently required.

A further object is to provide means whereby the proper sequence of operations of the motor controlling features is responsive to the operation of the controlling ele-

ment is positively and automatically insured and compelled.

With the above objects in view the invention consists in novel features of structure and combination, which will be set forth in detail as the description proceeds.

A preferred embodiment of the invention is illustrated in the accompanying drawings, wherein:

Figure 1 is a side elevation in which the usual parts of the truck are shown in broken lines and the parts in which the features of the invention are incorporated are shown in full lines.

Figure 2 is an elevation of the switch mechanism and certain connections for operating the resistor, the front cover of the switch mechanism being removed.

Figure 3 is an end view of the switch mechanism, the casing therefor being shown in section.

Figure 4 is a section on the line 4-4 of Figure 1 showing the brake and its operating connections.

Figure 5 is a diagram of the wiring of the motor, switch mechanism and resistor.

Figures 6 and 7 are an end view and an elevation, respectively, showing a modification of the connections for operating the resistor.

Figures 8 and 9 are similar views showing another modification of the same.

Figures 10 and 11 are similar views showing a further modification of the same.

The truck includes a frame 1 supported by front and rear wheels (whereof only the rear wheels 2 are shown), a propelling motor 3 connected by suitable gearing 4 (not shown as to details) to the rear wheels, a load carrying platform 5 located in front of the wheels 2 and an operator's platform or step 6 located behind the wheels 2. A suitable upright framework, generally designated 7, is arranged between the platform 5 and step 6 as the support for the various parts necessary for the operation of the truck, these parts including the motor 3 and gearing 4, the storage batteries mounted in a box 8 and the switch mechanism 9 which may be conveniently arranged adjacent the rear wall of the box 8.

The speed of the motor 3 is regulated entirely by a variable resistance 10 which is employed in conjunction with a normally closed main switch and is operated by a con-

trolling element having no connection with said main switch. The variable resistance is preferably of the compression type, which, being well known, does not require to be shown or described in detail. For present purposes it will be sufficient to point out that as applied to industrial trucks a resistance unit of the compression type preferably includes as the resistance medium a 10 suitably large number, e. g., upward of a hundred, (according to the capacity required) of contacting discs of suitable material, graphite being chiefly employed, which discs are arranged in a column in an 15 insulated container and are subject to varying mechanical pressure applied by a head in circuit with a terminal electrode, the head being actuated by an axially located and movable adjusting rod 11 which extends 20 through one end of the container.

The current flows to the motor 3 through a main switch 9^a which differs from the controller ordinarily employed in that it does not have variable speed contacts and further 25 in that it encompasses the functions of the usual separate reversing switch. For the regulation of the direction of the motor the main switch includes four movable contacts 12, 13, 14 and 15 and four stationary contacts 12^a, 13^a, 14^a and 15^a. The contacts 12, 13, 14 and 15 are preferably carried by a drum 16 fixedly mounted on the switch shaft 17. There is also provided a switch 9^b by which the resistor 10 may be short circuited, 30 i. e., which may be substituted for the resistor in the circuit of the main switch, and which, in the construction shown and preferred, comprises a movable contact 18, carried by a drum 19 loosely mounted on the 35 shaft 17 and a pair of stationary contacts 18^a and 18^b with which the contact 18 may be engaged. The contacts 13 and 14 are wired to the contacts 15 and 12 respectively and are arranged to engage the respective 40 contacts 13^a and 14^a simultaneously with the engagement of the contacts 15 and 12 with the respective contacts 15^a and 12^a as when the motor is to be driven in one direction, say forward. To provide for the operation 45 of the motor in the reverse direction the contacts 15 and 12 are formed whereby, as engaged with the contacts 15^a and 12^a respectively, they may be simultaneously engaged with the contacts 14^a and 13^a respectively, 50 the drum 16 being movable to disengage the contacts 14 and 13 from the contacts 14^a and 13^a and thereafter to establish the engagement with said contacts 14^a and 13^a of the respective contacts 15 and 12. 55 The operation of the compression resistor is such that the rod 11 is forced inward to secure progressively better contact of the graphite discs and the resistance varies inversely with the compression, that is to say 60 the resistance decreases as the pressure on

the discs is increased by the continued inward movement of the rod 11 and vice versa. To prevent waste of current the rod 11 may have a degree of outward movement sufficient to break the contact of the discs and thus open the circuit through the resistor. According to the invention the operations of the switch 9^b and rod 11 are coordinated whereby the contact 18 engages the contacts 18^a and 18^b to short circuit the resistor when, and not before, the resistance of the discs has been reduced to minimum and disengages the contacts 18^a and 18^b as soon as the resistance commences to build up from minimum. 75 80

Figure 5 shows a wiring diagram from which the foregoing general features of operation will be apparent. One terminal of the battery 20 is connected to a wire 21 having a branch 21^a which is connected to an electrode 22 in permanent contact with the rod 11 and a branch 21^b which is connected to the contact 18^b. The other terminal of the resistor 10 is connected by a wire 23 to the contact 13^a and by a wire 24 to the contact 18^a. Assuming that the switch 9^a is set for the forward drive of the motor and that the current is passed through the resistor the circuit may be traced as follows: one terminal of battery 20, wire 21, wire 21^a, electrode 22, rod 11, resistor 10, wire 23, contacts 13^a, 13, 15 and 15^a, wire 25 and branches 25^a and 25^b, field windings of motor 3, branch wires 26^a and 26^b to wire 26, contacts 12^a, 12, 14 and 14^a, wire 27, brush 28, armature 29, brush 30, and wire 31 to the other terminal of battery 20. If, however, with the current again passed through the resistor, the switch be set for the reverse drive of the motor the current of course flows through the field windings of the motor in the opposite direction and the circuit may be traced as follows: one terminal of battery 20, wire 21, branch 21^a, electrode 22, rod 11, resistor 10, wire 23, contacts 13^a, 12 and 12^a, wire 26, branches 26^a and 26^b, field windings of motor 3, branch wires 25^a and 25^b, wire 25, contacts 15^a, 15 and 14^a, wire 27, brush 28, armature 29, brush 30, and wire 31 to the other terminal of the battery 20. Assuming that the resistor is short circuited by the engagement of the contact 18 with the contacts 18^a and 18^b the circuits are traced as in the preceding instances except that the current instead of flowing through the resistor to the wire 23 is shunted by the branch 21^b, contacts 18^b, 18 and 18^a and wire 24 to the wire 23. 100 105 110 115 120 125

As shown and preferred the controller shaft 17 is arranged horizontally and the resistor 10 extends parallel to said shaft. The shaft 17 is journaled in the end walls 32 of the switch casing 33 which casing encloses the bar 34 upon which the sta- 130

tionary contacts 18^a, 18^b, 12^a, 13^a, 14^a and 15^a are mounted. The shaft 17 is operated by hand to establish the engagement of the contacts 12, 13, 14 and 15 in the manner described and for this purpose is extended through an end wall of the casing 33 and provided with an operating handle 35. The handle 35 is formed at one end with a squared opening in which the squared end 10 of the shaft 17 may be conformably engaged whereby the handle may be removed from the shaft. The contacts 12, 13, 14 and 15 are so arranged that the contacts 12 and 15 are at all times engaged with the contacts 12^a and 15^a, the contacts 13 and 14, only, are engaged with the respective contacts 13^a and 14^a when the drum 16 is moved to its upward limit, the contacts 12 and 15, only, are engaged with the respective contacts 13^a and 14^a when the drum 20 is moved to its downward limit, and in an intermediate position of the drum the contacts 13^a and 14^a are not engaged by either pair of contacts 13 and 14, or 12 and 15. It is desirable that the handle 35 be removable from the shaft 17 only when the drum 16 is in its intermediate or "off" position. For this purpose a cylindrical casting or gate 36 may be secured to a frame 30 part in surrounding relation to the shaft 17 and the hub portion of the handle 35; the gate 36 has a circumferential slot 37 through which the handle 35 projects and a longitudinal slot 38 extending to its outer 35 end and through which said handle may be removed in the neutral position of the shaft 17. In order that the drum 16 may be secured in any of its three positions but without obstruction to its ordered movement a suitable friction latch may be provided which, as shown and preferred, consists of a spring pressed ball 39 fitted in the bearing for the shaft 17 at one side of said shaft and engageable in recesses 40 formed or 45 provided in the adjacent end of said drum.

With the main switch set in either of its "on" positions the movement of the truck is wholly subject to a single controlling element which preferably comprises a pedal 41 mounted in juxtaposition to the operator's step 6. According to the invention mechanism is provided for connecting this pedal to the compression rod 11 of the resistor, to the short circuiting switch 9^b 50 and preferably also to the brake in such way that the operations of these elements are co-ordinated to one another and are responsive to a single movement of the pedal in either direction.

In the construction preferred the compression rod 11 is urged outward by a spring 42 and is forced inward by an axially movable operating stem 43 which includes a shank 60 provided with quick acting threads 44 working in a relatively stationary nut 45. When

the stem 43 is turned about its longitudinal axis it will move axially in one direction or the other according to the direction in which it is turned. In one direction of its axial movement it will engage the rod 11 and force the same inward in opposition to the spring 42, thereby progressively to increase the compression of the discs of the resistor 70 10 and progressively to reduce the resistance. In the opposite direction of axial movement 75 the stem 43 permits the rod 11 to be moved outward by the spring 42 whereby the pressure on the discs of the resistor is progressively reduced and the resistance progressively builds up. After the resistance has 80 reached maximum the further outward movement of the rod 11 will result in the discs becoming spaced from one another at one or more points whereby the current path through the resistor is broken. The rod 11 85 is preferably provided with an insulated tip 46 of hard metal to take the contact of the stem 43. The nut 45 is preferably adjustable whereby the stem 43 may be set as desired in relation to the rod 11. For this 90 purpose said nut has threaded engagement in a fixed bracket 47 and is provided with a suitably formed adjusting head 48 by which it may be turned. A latch 49 of suitable form is provided to hold the nut 45 against 95 accidental displacement and preferably consists of a stud screw fitted in the bracket 47 and engaging in any one of a series of recesses formed in the peripheral face of the head 48. 100

The stem 43 is provided with an arm 50 by which it may be rocked and in the construction preferred is connected to the drum 19 of the short circuiting switch by means of a link 51 pivoted to said arm and to a lug on said drum. The hub portion of the arm 50 preferably has a tapering fit on the stem 43 and is keyed thereto, being held against endwise displacement by a nut 52 threaded upon the end of said stem. The connections of the link 51 have lateral and end play sufficient to permit said link to act without binding in consequence of the endwise movement of the arm 50 with the stem 43. 110

Linkage connections are preferably used to connect the pedal 41 to the arm 50. These include an upper two-armed lever 53 and a lower lever 54 preferably provided with an angularly extending third arm 55. The pedal 41 is connected by a link 56 to an arm 115 of the lever 53, the opposite arm of which is connected by a link 57 to one of the alining arms of the lever 54. The opposite alining arm of the lever 54 is connected by a link 58 to the arm 50 at a point beyond the connection of the link 51. 120

The pedal 41 is normally held raised by a suitable spring 59 and by virtue of the connections described its movement in either direction is positively transmitted. The 130

contacts of the short circuiting switch are engaged only when the pedal is fully depressed. The extremes of compression of the discs of the resistor are obtained in the extreme positions of the pedal, the maximum compression being effected when the pedal is fully lowered and the minimum or, more exactly, the zero of compression being effected when the pedal is fully raised. The rod 11 is moved throughout the movement of the pedal in either direction, being moved inward when the pedal is lowered and outward when the pedal is raised. The engagement of the contacts of the short circuiting switch is the final effect in the movement of the pedal to its extreme downward limit and the disengagement of said contacts is the initial effect in the movement of the pedal from its extreme downward limit. In any movement of the pedal between its extreme upper position and a lower position short of its extreme lower position no operation of the short circuiting switch is produced, merely an idle movement of the contact 18, and the resistor 10 functions throughout, the resistance being varied according to the direction and extent of the pedal movement.

The invention also includes the control of the brake by the pedal 41 in connection with its movements to control the operations of the short circuiting switch and the resistor. For this purpose the arm 55 of the lever 54 is utilized. The brake is preferably of the construction shown which consists of a pair of semi-circular shoes 60 engageable with a drum 61 fitted on the shaft of the motor 3. The shoes 60 are pivotally connected as at 62 whereby they may be spread apart or drawn together and at their free ends are provided with extensions 63, which are acted on by a brake-operating spring 64. As shown a laterally directed rod 65 carried by one of the extensions projects slidably through an opening in the other upon which the spring 64 directly bears, the spring being mounted on said rod and exerting its thrust against a nut or head at the free end of the rod. The shoes 60 are disengaged from the drum 61 by a brake releasing cam 66 arranged between and acting on the extensions 63 and mounted on a rock shaft 67 having support by means of a suitable bearing 68. The shaft 67 is provided with a lever arm 69 which is connected by a link 70 to the arm 55. As the pedal 41 is lowered to provide for the propulsion of the truck at increased speed the cam 66 is turned so as to spread the shoes 60 and hold them disengaged from the drum 61. As the pedal is raised to reduce the speed at which the truck is driven the cam 66 is turned so as to permit the shoes 60 to move toward one another under the pressure of the spring 64. Substantially at the time the pedal reaches its extreme upper position the spring 64 effects

the complete engagement of the shoes 60 upon the drum 61, thereby to arrest the rotation of the motor shaft.

It will thus be seen that when the pedal 41 is fully raised the brake is applied while at the same time the current path through the element 10 is broken, thereby to prevent the flow of current to the motor. Of course, if desired, instead of breaking the current path through the resistor, as is preferred, the resistor could be so designed that when the pedal was fully raised it would still be in circuit with the main switch but with the resistance sufficiently great to prevent the flow of current to the motor in any substantial degree. When it is desired to move the truck the pedal is depressed (the action of its supporting spring preventing it from being depressed too rapidly) with the first effect of releasing the brake and the continuous effect of progressively reducing the resistance in the element 10. The truck thus starts with a slow and safe accelerating speed and its rate of movement can be steadily increased or decreased as required. Assuming that it is desired to drive the truck at full speed the pedal is depressed to its downward limit and when this is reached the short circuiting switch is closed, operating in the present embodiment, in the manner previously explained, to cut out the resistor 10. At the time the short circuiting switch is closed the resistance of the element 10 has been reduced to minimum so that the difference of potential between the current flowing through the resistor and the full strength of the current flowing through the short circuiting switch is very small from which it follows that operation of the short circuiting switch, either in closing or opening, will be without arcing. When it is desired to bring the truck to a stop the pedal is released and as it completes its upward movement effects the application of the brake and at the same time opens the circuit of the motor at the resistor 10.

It will be noted that the speed of the truck is controlled wholly by the pedal 41 and that all phases of speed regulation are automatically taken care of. The truck, moreover, in the embodiment described, has no fixed speeds but may be driven at any speed desired, the selection and control of the speed being analogous, both in manner and effect, to that obtained by the foot operated accelerator of an automobile operated by an internal combustion engine. This facility of speed control also insures safety of operation, since the speed may be instantly selected as conditions may require and indefinitely maintained at as low a rate as may be found necessary and since the hands of the operator are left free so that he may readily steady himself on the platform 6.

The slow, gradual and steady application

of current to the motor incident to the system of control described is of further advantage in that shocks are eliminated and vibrations minimized so that all parts of the truck mechanism will have a substantially longer efficient life.

Figures 6 to 11, inclusive, show certain alternative connections which may be employed to effect and control the operation 10 of the compression rod 11 of the resistor. In Figures 6 and 7 the arm 50^a (corresponding to the arm 50) is mounted on a rock shaft 43^a provided with a cam 44^a for engagement with the tip 46 of the rod 11. In Figures 8 15 and 9 a rock shaft 43^b is arranged along an axis at a right angle to the resistor and is provided with an arm 50^b to which the link 58 is connected and with a cam arm 44^b for engagement with the tip 46 of the rod 11. In Figures 10 and 11 the arm 50^c to which the link 58 is connected is incorporated in a 20 bell crank lever mounted on a supporting stud 43^c, the other arm 44^c engaging the tip 46.

25 Safety of operation, from the standpoints of obtaining a slow starting speed and of preventing an overload on the motor, requires that the resistor 10 shall function to reduce the resistance in the motor circuit 30 from maximum to minimum prior to the operation of the short circuiting switch and it is therefore indispensable that the truck shall be operated in the manner described. The invention provides means for compelling 35 such operation, the means consisting of an interlock between the drum 16 of the reversing switch and the drum 19 of the short circuiting switch whereby the drum 16 of the reversing switch cannot be moved from 40 either of its operative positions except when the short circuiting switch is fully opened and, preferably, the normal circuit of the resistor is broken, (thus making it necessary to bring the truck to a standstill and completely open the circuit of the motor before 45 the reversing switch can be operated to change the direction of movement), and the drum 19 of the short circuiting switch cannot be moved to close said switch except 50 when the drum 16 of the reversing switch is in either of its "on" positions, that is to say the drum 19 cannot be operated to close the short circuiting switch when the reversing switch is in neutral position or prior to 55 an actuation of said reversing switch. In the construction preferred the interlocking means for the drums 16 and 19 includes a locking ball 71 which is confined in and freely movable through an opening 72 60 formed in a supporting plate 73 interposed between the ends of the drums 16 and 19, the ball 71 being greater in diameter than the thickness of said plate whereby it will always project from one face of said plate 65 or the other. The drum 16 carries an end

plate 74 which is formed with recesses 75 and 76 conforming to the ball 71 and arranged to co-operate with said ball in the lower and upper positions, respectively, of said drum. The drum 19 carries an end 70 plate 77 provided with a recess 78 conforming to the ball 71 and arranged to co-operate with said ball in the extreme upper position of said drum. A flat web 79 extends between the recesses 75 and 76, closely adjacent the plate 73 and co-operates with the ball 71 in the neutral position of the drum 16. The plate 77 is likewise arranged closely adjacent the plate 73 and co-operates with the ball 71 in any lowered position of the 80 drum 19.

When the truck is being driven the drum 19 is lowered more or less and the ball 71 is held by the plate 77 in engagement in either of the recesses 75 or 76, accordingly 85 as the reversing switch is set for forward or reverse direction of movement, said ball thus positively locking the drum 16 of the reversing switch in the position in which it was previously set by means of the handle 90 35. This positive action of the ball 71 to lock the reversing switch drum 16 in either of its operative positions is maintained so long as the drum 19 is held out of its uppermost position by means of the pedal 41. 95 However, when the pedal is released for the purpose of bringing the truck to a stop the drum 19 of the reversing switch is raised to its uppermost position in which the recess 78 aligns with the ball 71 and at such time the locking action of said ball on the drum 16 is not maintained. Thereupon, with the truck at a standstill, the drum 16 of the reversing switch may be moved into neutral position or into the position to reverse 100 the direction of movement of the truck. Assuming that the drum 16 is moved into neutral position the web 79 will act on the ball 71 and positively hold said ball engaged in the recess 78 so as to lock the drum 19 in 110 its uppermost position. It follows that so long as the drum 16 is in neutral position the drum 19 of the short circuiting switch is positively locked in open position and cannot be moved from such position. When 115 however, the drum 16 is set for the drive of the truck in either direction the ball 71 will align with either of the recesses 75 or 76, according to the position of the drum 16 120 and at such time the locking action of the ball 71 on the drum 19 is no longer maintained, whereby the drum 19 may be freely moved and the short circuiting switch may be closed in the regular manner if so desired, 125 the movement of the drum 19 from its uppermost position being effective by means of the plate 77 to hold the ball 71 engaged in the recess 75 or 76, as the case may be.

It will be understood that the embodiment described is preferred, as now considered, 130

but that the invention is susceptible of embodiment in modified forms and therefore that the specific description of the structural details as herein disclosed is not to be taken as imposing any limitations upon the appended claims or otherwise than for due purposes of exposition.

Having fully described my invention, I claim:

- 10 1. In an industrial truck, in combination, an electric propelling motor, a source of electrical energy, a reversing switch, a variable resistance element normally in circuit with said motor, switch and source, a short circuiting switch in the circuit of the motor and main switch, a foot operated controlling element, and operative connections between said controlling element and said short circuiting switch and resistance element whereby in either direction of its movement said controlling element operates said resistance element progressively to increase or decrease the resistance and as it approaches or recedes from the limit of its movement in one direction closes or opens said short circuiting switch, the latter being closed by said controlling element only when the resistance has been reduced to minimum.
- 20 2. In an industrial truck, in combination, an electric propelling motor, a source of electrical energy, a reversing switch, a variable resistance element normally in circuit with said motor, switch and source, a short circuiting switch in the circuit of the motor and main switch, a brake for arresting the movement of the truck, a controlling element, and means operatively connecting said controlling element to said resistance element, short circuiting switch and brake, whereby said controlling element as it is moved in one direction or the other operates said resistance element progressively to increase or decrease the resistance, as it approaches or recedes from the limit of its movement at which the resistance is maximum effects the application or release of said brake, and as it approaches or recedes from the opposite limit of its movement at which the resistance is minimum closes or opens said short circuiting switch and cuts out or cuts in said resistance element.
- 30 3. In an industrial truck, in combination, an electric propelling motor, a source of electrical energy, a reversing switch, a variable resistor of the compression type normally in circuit with said motor, switch and source and having a movable part by which the resistor is regulated, a short circuiting switch operative to cut said resistor out of circuit, a brake for arresting the movement of the truck, a foot operated controlling element, and means operatively connecting said controlling element to said movable part, short circuiting switch and
- 40 4. In an industrial truck, in combination, an electric propelling motor, a source of electrical energy, a reversing switch, a variable resistor of the compression type normally in circuit with said motor, switch and source, and having a movable part by which the resistance is regulated, a short circuiting switch operative to cut said resistor out of circuit, a pedal, an actuating element for operating said movable part, operative connections between said actuating element and said short circuiting switch, and operative connections between said pedal and said actuating element, whereby said pedal as it is moved in one direction or the other continuously operates said movable part to increase or decrease the resistance, and as it approaches or recedes from the limit of its movement at which the resistance is minimum closes or opens the short circuiting switch to cut out or cut in said resistor.
- 50 5. In an industrial truck, in combination, an electric propelling motor, a source of electrical energy, a reversing switch, a variable resistor of the compression type normally in circuit with said motor, switch and source, and having a movable part by which the resistance is regulated, a short circuiting switch operative to cut said resistor out of circuit, a pedal, an actuating element for operating said movable part, a link operatively connecting said actuating element and short circuiting switch, an upper lever, a lower lever, a link connecting said pedal and one arm of the upper lever and one arm of the lower lever and a link connecting another arm of the lower lever and said actuating element, whereby said pedal as it is moved in one direction or the other continuously operates said movable part to increase or decrease the resistance, as it approaches or recedes from the limit of its movement at which the resistance is minimum closes or opens the short circuiting switch to cut out or cut in said resistor.
- 60 6. In an industrial truck, in combination, an electric propelling motor, a source of electrical energy, a reversing switch, a variable resistor of the compression type normally in circuit with said motor, switch and source, and having a movable part by which the resistance is regulated, a short circuiting switch operative to cut said resistor out of circuit, a brake for arresting the movement of the truck, a foot operated controlling element, and means operatively connecting said controlling element to said movable part, short circuiting switch and

brake whereby said element as it is moved in one direction or the other continuously operates said movable part to increase or decrease the resistance, as it approaches or recedes from the limit of its movement at which the resistance is maximum effects the application or release of said brake, and as it approaches or recedes from the opposite limit of its movement at which the resistance is minimum closes or opens the short circuiting switch to cut out or cut in said resistor.

70 7. In an industrial truck, in combination, an electric propelling motor, a source of electrical energy, a reversing switch, a variable resistor of the compression type normally in circuit with said motor, switch and source, and having a movable part by which the resistance is regulated, a short circuiting switch operative to cut said resistor out of circuit, a pedal, an actuating element for operating said movable part, operative connections between said actuating element and said short circuiting switch, and operative connections between said pedal and said actuating element, whereby said pedal as it is moved in one direction or the other continuously operates said movable part to increase or decrease the resistance, and as it approaches or recedes from the limit of its movement at which the resistance is minimum closes or opens the short circuiting switch to cut out or cut in said resistor.

80 8. In an industrial truck, in combination, an electric propelling motor, a source of electrical energy, a reversing switch, a variable resistor of the compression type normally in circuit with said motor, switch and source, and having a movable part by which the resistance is regulated, a short circuiting switch operative to cut said resistor out of circuit, a pedal, an actuating element for operating said movable part, a link operatively connecting said actuating element and short circuiting switch, an upper lever, a lower lever, a link connecting said pedal and one arm of the upper lever and one arm of the lower lever and a link connecting another arm of the lower lever and said actuating element, whereby said pedal as it is moved in one direction or the other continuously operates said movable part to increase or decrease the resistance, as it approaches or recedes from the limit of its movement at which the resistance is minimum closes or opens the short circuiting switch to cut out or cut in said resistor.

90 9. In an industrial truck, in combination, an electric propelling motor, a source of electrical energy, a reversing switch, a variable resistor of the compression type normally in circuit with said motor, switch and source, and having a movable part by which the resistance is regulated, a short circuiting switch operative to cut said resistor out of circuit, a brake for arresting the movement of the truck, a foot operated controlling element, and means operatively connecting said controlling element to said movable part, short circuiting switch and

- sistance is regulated, a short circuiting switch operative to cut said resistor out of circuit, a brake for arresting the movement of the truck, a pedal, an actuating element 5 for operating said movable part, a link operatively connecting said actuating element and short circuiting switch, an upper lever, a lower lever, a link connecting the pedal and one arm of the upper lever, a link connecting the other arm of the upper lever and one arm of the lower lever, a link connecting another arm of the lower lever and said actuating element, a lever for controlling the 10 operation of said brake, and a link connecting a third arm of the lower lever and said brake controlling lever, whereby said pedal as it is moved in one direction or the other continuously operates said movable part to increase or decrease the resistance, as it approaches or recedes from the limit of its 15 movement at which the resistance is maximum effects the application or release of said brake, and as it approaches or recedes from the opposite limit of its movement at 20 which the resistance is minimum closes or opens the short circuiting switch to cut out or cut in said resistor.
7. In an industrial truck, in combination, an electric propelling motor, a source of electrical energy, a reversing switch, a variable resistance element normally in circuit with 30 said motor, switch and source, a short circuiting switch in the circuit of the motor and main switch, a brake for arresting the movement of the truck, a foot operated controlling element, and means operatively connecting said controlling element to said resistance element short circuiting switch and 35 brake whereby said controlling element as it is moved in one direction or the other operates said resistance element progressively to increase or decrease the resistance as it approaches or recedes from the limit of its movement at which the resistance is maximum 40 effects the application or release of said brake, and as it approaches or recedes from the opposite limit of its movement at which the resistance is minimum closes or opens said short circuiting switch and cuts 45 out or cuts in said resistance element.
8. In an industrial truck, in combination, an electric propelling motor, a source of electrical energy, a reversing switch, a variable resistance element normally in circuit with 55 said motor, switch and source, said element being operative to vary the speed of said motor in normal running, a foot operated controlling element, and operative connections between said controlling element and resistance element whereby in either direction of 60 its movement said controlling element operates said resistance element progressively to increase or decrease the resistance.
9. In an industrial truck, in combination, 5 an electric propelling motor, a source of 65 electrical energy, a reversing switch, a variable resistance element normally in circuit with said motor, switch and source, a brake for arresting the movement of the truck, a controlling element, and means operatively 70 connecting said controlling element to said resistance element and brake, whereby said controlling element as it is moved in one direction or the other operates said resistance element progressively to increase or 75 decrease the resistance and as it approaches or recedes from the limit of its movement at which the resistance is maximum, effects the application or release of said brake.
10. In an industrial truck in combination, an electric propelling motor, a source of electrical energy, a reversing switch, a variable resistance element normally in circuit with said motor, switch and source, a brake for arresting the movement of the truck, a foot operated controlling element and means operatively connecting said controlling element to said resistance element and brake, whereby said controlling element as it is moved in one direction or the other operates said resistance element progressively to increase or decrease the resistance and as it approaches or recedes from the limit of its movement at which the resistance is maximum effects the application or release of the said brake.
11. In an industrial truck, in combination, an electric propelling motor, a source of electrical energy, a reversing switch, a variable resistance element normally in circuit with said motor, switch and source, a short circuiting switch in the circuit of said motor and reversing switch, the latter having two extreme operative positions and an intermediate neutral position, a controlling element operatively connected to said resistance element and short circuiting switch, and means co-operating with said reversing switch and short circuiting switch whereby the short circuiting switch except in a definite open position locks the reversing switch in either of its extreme positions and the reversing switch when in neutral position locks the short circuiting switch in said open position, the controlling element as it is moved in one direction or the other operating said resistance element to increase or decrease the resistance and as it approaches or recedes from the limit of its movement at which the resistance has been reduced to minimum 100 closes or opens the short circuiting switch.
12. In an industrial truck, in combination, an electric propelling motor, a source of electrical energy, a reversing switch, a variable resistance element normally in circuit with said motor, switch and source, a short circuiting switch in the circuit of said motor and reversing switch, the latter having two extreme operative positions and an intermediate neutral position, a foot operated con-

trolling element operatively connected to said resistance element and short circuiting switch, and means co-operating with said reversing switch and short circuiting switch 5 whereby the short circuiting switch except in a definite open position locks the reversing switch in either of its extreme positions and the reversing switch when in neutral position locks the short circuiting switch in 10 said open position, the controlling element as it is moved in one direction or the other operating said resistance element to increase or decrease the resistance and as it approaches or recedes from the limit of its 15 movement at which the resistance has been reduced to minimum closes or opens the short circuiting switch.

13. In an industrial truck, in combination, an electric propelling motor, a source of electrical energy, a reversing switch, a variable resistance of the compression type normally in circuit with said motor, switch and source, and having a movable part by which the resistance is regulated, a short circuiting 20 switch operative to cut said resistor out of circuit, an operative connection between the short circuiting switch and said movable part, the reversing switch having two extreme operative positions and an intermediate neutral position, a foot operated controlling element operatively connected to said movable part, and means co-operating with said reversing switch and short circuiting switch whereby the short circuiting 25 switch except in a definite open position locks the reversing switch in either of its extreme positions and the reversing switch when in neutral position locks the short circuiting switch in said open position, the controlling element as it is moved in one direction or the other operating said resistor to increase or decrease the resistance and as it approaches or recedes from the limit of its 30 movement at which the resistance has been reduced to minimum closes or opens the short circuiting switch.

14. In an industrial truck, in combination, an electric propelling motor, a source of electrical energy, a reversing switch, a variable resistance element normally in circuit with said motor, switch and source, a short circuiting switch in the circuit of said motor and reversing switch, the latter having two extreme positions and an intermediate neutral position, and means co-operating with said reversing switch and short circuiting switch whereby the short circuiting switch except in a definite open position locks the reversing switch in either of its extreme positions and the reversing switch when in neutral position locks the short circuiting switch in said open position.

15. In an industrial truck, in combination, an electric propelling motor, a source of electrical energy, a reversing switch, a variable

resistance element normally in circuit with said motor, switch and source, a short circuiting switch in the circuit of said motor and reversing switch, the latter having two extreme operative positions and an intermediate neutral position, the resistance element having a movable part by which the resistance is regulated, an operative connection between said movable part and said short circuiting switch, and means co-operating with said reversing switch and short circuiting switch whereby the short circuiting switch except in a definite open position locks the reversing switch in either of its extreme positions and the reversing switch when in neutral position locks the short circuiting switch in said open position.

16. In an industrial truck, in combination, an electric propelling motor, a source of electrical energy, a reversing switch, a variable resistance element normally in circuit with said motor, switch and source, a short circuiting switch in the circuit of said motor and reversing switch, the latter having two extreme positions and an intermediate neutral position, means co-operating with said reversing switch and short circuiting switch whereby the short circuiting switch except in a definite open position locks the reversing switch in either of its extreme positions and the reversing switch when in neutral position locks the short circuiting switch in said open position, and a pedal constituting a common operating element for said variable resistance element and said short circuiting switch and operatively connected thereto whereby said pedal as it is moved in one direction or the other operates said resistance element to increase or decrease the resistance and as it approaches or recedes from the limit of its movement at which the resistance has been reduced to minimum closes or opens the short circuiting switch.

17. In an industrial truck, in combination, an electric propelling motor, a source of electrical energy, a reversing switch including a rotatably mounted drum, a variable resistance element normally in circuit with said motor, switch and source, a short circuiting switch in the circuit of said motor and reversing switch and including a drum mounted co-axially with the drum of said reversing switch for rotation independently thereof, said variable resistance element having a movable part by which the resistance is regulated, means for moving the drum of the short circuiting switch in connection with the operation of said movable part whereby the short circuiting switch is closed when the resistance is reduced to minimum, the drum of the reversing switch having two extreme operative positions and an intermediate neutral position, and means co-operating with said drums whereby the short circuiting switch

- except in a definite open position locks the reversing switch in either of its extreme positions and the reversing switch when in neutral position locks the short circuiting switch in said open position.
18. In an industrial truck, in combination, an electric propelling motor, a source of electrical energy, a reversing switch, a variable resistance element normally in circuit with said motor, switch and source, a short circuiting switch in the circuit of said motor and reversing switch, the latter having two extreme operative positions and an intermediate neutral position, and means 10 for preventing an operation of the short circuiting switch when the reversing switch is in neutral position and for preventing an operation of the reversing switch from either of its extreme positions except in a 15 definite open position of the short circuiting switch.
19. In an industrial truck, in combination, an electrical propelling motor, a source of electrical energy, a main switch, a variable 20 resistance element normally in circuit with said motor, switch and source, a short circuiting switch in the circuit of the motor and main switch the short circuiting switch having a movable element and a controlling 25 element operatively connected to said resistance element and positively connected to the movable element of the short circuiting switch and actuated by the truck operator, the main switch being closed throughout the 30 operation of the truck.
20. In an industrial truck, in combination, an electrical propelling motor, a source of electrical energy, a main switch, a variable resistor of the compression type normally in 35 circuit with said motor, switch and source, a short circuiting switch in the circuit of the motor and main switch, the short circuiting switch having a movable element and a controlling element operatively connected to 40 said resistance element and positively connected to the movable element of the short circuiting switch and actuated by the truck operator, the main switch being closed throughout the 45 operation of the truck.
21. In an industrial truck, in combination, an electrical propelling motor, a source of electrical energy, a variable resistance element normally in circuit with said motor and source, a short circuiting switch in the 50 circuit of said motor and source, a foot operated controlling element, and operative connections between said controlling element and said short circuiting switch and resistance element whereby in either direction of 55 its movement said controlling element operates said resistance element progressively to increase or decrease the resistance and as it approaches or recedes from the limit of its movement in one direction closes or opens 60 said short circuiting switch, the latter being 65 closed by said controlling element only when the resistance has been reduced to minimum.
22. In an industrial truck, in combination, an electrical propelling motor, a source of electrical energy, a variable resistance element of the compression type normally in circuit with said motor and source, a short circuiting switch in the circuit of said motor and source, a foot operated controlling element, and operative connections between 70 said controlling element and said short circuiting switch and resistance element whereby in either direction of its movement said controlling element operates said resistance element progressively to increase or decrease the resistance and as it approaches or recedes from the limit of its movement in one direction closes or opens 75 said short circuiting switch, the latter being closed by said controlling element only when the resistance 80 has been reduced to minimum.
23. In an industrial truck, in combination, an electrical propelling motor, a source of electrical energy, a variable resistance element of the compression type normally in 85 circuit with said motor and source, said element being operative to vary the speed of said motor in normal running, a spring held foot operated controlling element, and operative connections between said controlling 90 element and said resistance element.
24. In an industrial truck, in combination, an electrical propelling motor, a source of electrical energy, a variable resistance element normally in circuit with said motor and source, a brake, a foot operated controlling element, and operative connections between said controlling element and said 95 resistance element and brake.
25. In an industrial truck, in combination, an electrical propelling motor, a source of electrical energy, a variable resistance element normally in circuit with said motor and source, a brake, a controlling element actuated by the operator and operative connections between said controlling element and said resistance element and brake.
26. In an industrial truck, in combination, an electrical propelling motor, a source of electrical energy, a main switch, a variable 100 resistance element normally in circuit with said motor, switch and source, a foot operated controlling element, operative connections between said controlling element and said resistance element, and means for automatically preventing an actuation of said switch to open the same at any period of the movement of said controlling element beyond its initial position.
27. In an industrial truck, in combination, an electrical propelling motor, a source of electrical energy, a main switch, a variable resistance element normally in circuit with said motor, switch and source, a foot operated controlling element, operative connec- 105

tions between said controlling element and said resistance element, and means for automatically preventing an actuation of said controlling element while the main switch 5 is open.

28. In an industrial truck, in combination, an electrical propelling motor, a source of electrical energy, a main switch, a variable resistance element normally in circuit with 10 said motor, switch and source, a foot operated controlling element, operative connections between said controlling element and said resistance element, and means for automatically preventing an actuation of said 15 switch to open the same at any period of the movement of said controlling element beyond its initial position and for automatically preventing an actuation of said controlling element while the main switch is 20 open.

29. In an industrial truck, in combination, an electrical propelling motor, a source of electrical energy, a main switch, a variable resistance element normally in circuit with 25 said motor, switch and source, a controlling element, operative connections between said controlling element and said resistance element and means for automatically preventing an actuation of said main switch to

open the same at any period of the movement of said controlling element beyond 30 its initial position.

30. In an industrial truck, in combination, an electrical propelling motor, a source of electrical energy, a main switch, a variable 35 resistance element normally in circuit with said motor, switch and source, a controlling element, operative connections between said controlling element and said resistance element and means for automatically preventing 40 an actuation of said controlling element while the main switch is open.

31. In an industrial truck, in combination, an electrical propelling motor, a source of electrical energy, a main switch, a variable 45 resistance element normally in circuit with said motor, switch and source, a controlling element, operative connections between said controlling element and said resistance element and means for automatically preventing 50 an actuation of said main switch to open the same at any period of the movement of said controlling element beyond its initial position and for automatically preventing an actuation of said controlling element while the main switch is open.

In testimony whereof I affix my signature.

WILLIAM C. CARR.
